(57) **CLAIM**

We claim the ornamental design for a television with rollable display, as shown and described.

DESCRIPTION

FIG. 1 is a perspective view of a television with rollable display showing our new design in a first position of use; FIG. 2 is a front elevation view thereof; FIG. 3 is a rear elevation view thereof; FIG. 4 is a left-side elevation view thereof; FIG. 5 is a right-side elevation view thereof; FIG. 6 is a top plan view thereof; FIG. 7 is a bottom plan view thereof; FIG. 8 is a perspective view of the television with rollable display of FIG. 1 shown in a second position of use; and, FIG. 9 is a perspective view of the television with rollable display of FIG. 1 shown in a third position of use. Broken lines within the screen shown in FIGS. 8 and 9 illustrate environmental subject matter and form no part of the claimed design. All other broken lines and adjacent unshaded surfaces in FIGS. 8 and 9 depict portions of the television with rollable display that form no part of the claimed design.
